EUGENIO N. DE ALCOCER AND FRANCISCO O. DE ALCOCER, OF MEXICO CITY, MEXICO.

TWISTING DEVICE.

Application filed August 29, 1924. Serial No. 735,043.

To all whom it may concern:

Be it known that we, EUGENIO N. DE ALCOCER and FRANCISCO O. DE ALCOCER, citizens of Mexico, and residents of Mexico City, Mexico, have invented a new and Improved Twisting Device, of which the following is a full, clear, and exact description.

This invention relates to devices for twisting together a plurality of cords or strands of material in order to form a heavier cord or rope and has particular reference to a device of this character which is preferably detachably connected with and operable by the bobbin winder of a sewing machine.

The invention furthermore includes an element which is adapted for connection with a stationary member for supporting the opposite ends of the cords or strands to be twisted.

One of the principal objects of the present invention is to provide an extremely simple and improved twisting device which functions to uniformly twist together a plurality of cords or strands to produce a heavier cord or rope and which is found capable of use to uniformly cover one strand by a plurality of helically wound strands of material.

As a still further object the invention comprehends in a twisting device, means for compensating for the decrease in the length of the strands being twisted in order to prevent breakage of the strands under the twisting action.

The invention furthermore aims to provide a twisting device of the character set forth which is extremely simple in its construction and mode of operation, which is inexpensive to manufacture and which is highly efficient in its purpose. I would have it understood that my device could as well be used for making cord and rope out of ribbon, such as crepe paper ribbon, etc., silk ribbon, and the like.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the

full extent indicated by the general meaning of the terms in which the claims are expressed.

55

In the drawings—

Figure 1 is a side elevation of the twisting device in use and as applied to a sewing machine bobbin winder;

Figure 2 is an enlarged view with parts 60 in section to disclose the underlying structure;

Figure 3 is a perspective view of a slightly modified use of the invention;

Figure 4 is a side elevation of the driving 65 element which cooperates with the bobbin winder of the machine;

Figure 5 is an end view thereof; and

Figure 6 is a top plan view of the element for supporting the opposite end of the 70 strands.

Referring to the drawings by characters of reference A designates a sewing machine provided with the usual bobbin winding device B which is operated by the driving belt 75 C of the machine and which bobbin winding device is provided with a rotary shaft D. E represents the back of a chair or other fixed object which is spaced from the machine and F the strands or cords which are 80 to be twisted together for the purpose of producing the heavier cord or rope.

The device for effecting the twisting comprises a drive element 10 which is provided with a solid head 11 at one end and with a 85 substantially cylindrical axially projecting sleeve 12 at its opposite end which is slotted inwardly from its open end as at 13 to provide a multiplicity of radially contractible spring fingers 14. The solid end is provided 90 with a substantially triangular looped element 15 with which one end of the strands F are associated. A supporting element designated generally by the reference character 16 is designed for the opposite ends of the 95 strands and in the preferred use of the device said element is designed to hold the strands in a fixed relation while the driving element 10 rotates the strands to effect the intertwisting thereof. The element 16 includes a spring clip 17 having spaced resilient legs 18 and 19. The leg 19 is provided with an outwardly offset portion 20 which is apertured as at 21. A stud bolt 21 having a

headed end 22 and a threaded end 23 is inserted through the aperture 21 with a retaining nut 24 threadedly engaged thereon and lying within the offset portion 20. Adjacent its outer headed end 22 the stud bolt 5 has mounted thereon a sleeve member 25 with which a substantially triangular looped element 26 is swingingly connected. A washer 27 is interposed between the sleeve member 10 25 and the outer face of the offset portion 20 and the sleeve member 25 is clamped in place by engaging a screw driver in the kerf 28 of the head 22. In order to compensate for the reduction in the length of the strands F as 15 they are twisted, the ends G of the strands are associated with the eye H at the outer end of a coiled contractile spring J the inner end K of which is engaged with the triangular loop 26. It thus follows that when the 20 spring clip 17 is engaged with a fixed object E such as the back of a chair or the like and the sleeve 12 is coupled with the shaft D of the bobbin winder, that operation of the bobbin winder will effect a rotation of the driving element 10 to cause the twisting of the strands F. It is of course obvious 25 that as the twisting of the strands F takes place, the coiled contractile spring J will stretch to compensate for the decrease in the length of the strands.

In some instances it has been found desirable to cover a central strand or wire L with an outer helically associated covering strip M and in this instance the stud screw 35 21 as illustrated in Figure 3 is unscrewed to release the sleeve 25 from the clamping action so that the sleeve is swivelled on the stud screw for rotation with the central strand or wire L as the same is rotated by 40 the driving element 10. The operator after associating the outer covering strip M with one end of the wire L proceeds to feed the same throughout the length of the central strand or wire L so that the outer strip is 45 helically wound thereon.

We claim:

1. A twisting device of the character described comprising a rotary thimble like driving element, means on said driving element for associating therewith one end of the strands of the material to be twisted, said driving element being split to provide a series of fingers for spring fitting said driving element over the end of a driving shaft.

2. A twisting device of the character described comprising a rotary driving element, means on said driving element for associating therewith one end of the strands of material to be twisted, and means for detachably associating the driving element with a driving shaft, rotatable means holding the other ends of said strands, and means for optionally locking said rotatable means against rotation.

3. The combination with a sewing machine including a bobbin winding drive element of a twisting attachment including a driven element carrying a loop for receiving the ends of strands to be twisted, a carrying tensioning element including a spring clamping member for detachable engagement with a suitable support at a distance from the sewing machine, a tensioning means 70 connecting said clamp and the other ends of the strands to be twisted.

4. The combination with a sewing machine including a bobbin winding drive element of a twisting attachment including a driven element carrying a loop for receiving the 80 ends of strands to be twisted, a carrying tensioning element including a spring clamping member for detachable engagement with a suitable support at a distance from the sewing machine, a tensioning means connecting said clamp and the other ends of the strands to be twisted, means for selectively preventing or permitting rotation of the tensioning means.

5. In a device of the class described, 90 means for supporting one end of a flexible device during twisting, including a spring bracket engageable with a support, a sleeve associated with the bracket, means for optionally locking the sleeve against rotation, 95 a bail pivoted to the sleeve and a tensioning spring adapted to connect the bail and one end of the strand to be twisted.

6. Means for supporting one end of a strand during twisting, including a detachable 100 clamping member engagable with a support, a sleeve mounted to rotate on the exterior of said clamping member, a screw on which said sleeve normally rotates, means for tightening the screw to hold said sleeve 105 against rotation, a bail carried by the sleeve and means for attaching one end of a strand to the bail.

7. In a device of the class described, a 110 pair of pivoted bails between which a strand is adapted to be held during twisting, a thimble-like driving element connected to one bail and adapted to frictionally fit the end of a driving shaft, a rotatable sleeve carrying the other bail, means for mounting 115 the sleeve on a support.

8. In a device of the class described, a 120 pair of pivoted bails between which a strand is adapted to be held during twisting, a thimble-like driving element connected to one bail and adapted to frictionally fit the end of a driving shaft, a rotatable sleeve carrying the other bail, means for mounting the sleeve on a support, and a tensioning spring adapted to connect one end of the 125 strand with one of the bails.

9. The combination with a sewing machine including a rotating stub shaft of means for supporting one end of a strand to be twisted, including a driven element fric- 130

tionally fitted over the end of the stub shaft, and a bail carried by said element.

10. In a twisting device a pair of supports for attachment to opposite ends of a strand 5 to be twisted, one of said supports including means for detachable engagement with a stationary supporting member, the other of

said supports including means for detachable engagement with a rotatable driving element, each of said supports including 10 swinging bails and a helical tensioning spring carried by one of the bails.
